The combination caulking tube cap and applicator, as shown and described.

DESCRIPTION

FIG. 1 is a perspective view of the combination caulking tube cap and applicator wherein the phantom lines depict a caulking tube which forms no part of the present invention;

FIG. 2 is a top plan view thereof;

FIG. 3 is a bottom plan view thereof;

FIG. 4 is a front side elevational view thereof;

FIG. 5 is a rear side elevational view thereof;

FIG. 6 is a left side elevational view thereof; and,

FIG. 7 is a right side elevational view thereof.
